Primary Examiner — Mary Ann Calabrese*Assistant Examiner* — Jennifer L Rempfer(74) *Attorney, Agent, or Firm* — Donald J. Ranft; Collen(57) **CLAIM**

The ornamental design for a dry erase board partition, as shown and described.

DESCRIPTION

Fig. 1.1 is a rear view of a dry erase board partition in a folded state showing my new design;

Fig. 1.2 is a front view in an unfolded state thereof;

Fig. 1.3 is a side view in an unfolded state thereof;

Fig. 1.4 is a side view in an unfolded state thereof;

Fig. 1.5 is a side view in a folded state thereof;

Fig. 1.6 is a top view in an unfolded state thereof;

Fig. 1.7 is a rear view in an unfolded state thereof;

Fig. 1.8 is a bottom view in an unfolded state thereof;

Fig. 1.9 is a rear view in a folded state thereof;

Fig. 1.10 is a left side view in an unfolded state thereof; and

Fig. 1.11 is a right side view in an unfolded state thereof.
